HYDRAULIC WEDGE

Christopher Brady Evenson, Cottage Grove, Oreg.

Application April 22, 1952, Serial No. 283,627

4 Claims. (Cl. 254—104)

1

This invention relates to a hydraulic wedge, and more particularly to a hydraulic wedge for use in felling heavy trees or other woodworking jobs.

This invention is an improvement over the hydraulic wedge of my copending application, Serial No. 112,393, now Patent No. 2,657,904, granted November 3, 1953.

The object of the invention is to provide a hydraulic wedge which is adapted to be actuated by hydraulic fluid that is supplied by a pump that is operated by a saw chain, whereby the wedge can be positioned in a cutout in a tree to fell the tree or prevent binding or pinching of a saw that is being used.

Another object of the invention is to provide a hydraulic wedge which includes a pair of manually operable valves or cocks for regulating the movement of the wedge, there being ball bearings for insuring smooth movement of the parts.

A further object of the invention is to provide a hydraulic wedge which is extremely simple and inexpensive to manufacture.

Other objects and advantages will be apparent during the course of the following description.

In the accompanying drawings forming a part of this application, and in which like numerals are used to designate like parts throughout the same:

Figure 1 is a side elevational view, with parts broken away and in section, showing the wedge of the present invention with the dependent parts for operating the wedge;

Figure 2 is a top plan view of the hydraulic wedge, constructed according to the present invention;

Figure 3 is a longitudinal sectional view taken through the wedge of the present invention;

Figure 4 is a view similar to Figure 3, but with the jaws in their expanded position;

Figure 5 is a fragmentary sectional view illustrating the valve mechanism;

Figure 6 is a transverse vertical sectional view taken through the valve mechanism;

Figure 7 is a transverse sectional view taken through the wedge unit;

Figure 8 is a sectional view showing one of the elliptical bearings;

Figure 9 is a view similar to Figure 8, but showing a modification wherein a ball bearing is used in lieu of the elliptical bearings;

Figure 10 is an enlarged, fragmentary, sectional view showing one of the end wedge guides;

Figure 11 is a vertical, longitudinal, sectional view of the hydraulic pump;

2

Figure 12 is a top plan view of the wedge construction, with the ball bearings removed;

Figure 13 is an enlarged elevational view of one of the spring assemblies;

Figure 14 is a plan view of the structure shown in Figure 13.

Referring in detail to the drawings, the numeral 30 designates the wedge unit of the present invention, Figure 1, while the numeral 31 designates a tank which is adapted to hold hydraulic fluid. A pump 32 is provided for pumping hydraulic fluid from the tank 31 through a conduit 33, thence through a conduit 34, into the wedge unit 30, for actuating the latter. A return conduit 35 is provided for the passage of hydraulic fluid from the wedge unit 30 back into the tank 31.

The assembly is operated by means of a power-driven chain saw 36, and the saw 36 includes a driven shaft 37 that has a cam 38 mounted thereon. The cam 38 is arranged in engagement with a roller 39, the roller 39 being rotatably connected to an arm 40. The other end of the arm 40 is pivotally connected by a pin 41 to a supporting body 45, and a pin 41 serves to pivotally connect the arm 40 to the upper end of a stem or rod 42 which forms part of the pump 32.

The lower or inner end of the stem 42 is provided with a piston 43. The pump 32 includes a body 53 which is provided with a compartment or chamber 46 therein, Figure 11, and a bracket 47 extends from the bottom of the body 53 so that a suitable securing element 48 can be used for connecting the body 53 to a supporting structure 49.

Figure 1. A pair of check valves 50 and 51 are arranged in the body 53, and the check valves serve to insure that hydraulic fluid will not be accidentally pumped in the wrong direction through the conduits 33 and 34. Thus, upon actuation of the saw 36, the arm 40 will be pivoted about the pin 41, whereby the piston 43 will reciprocate in the body 53 to thereby cause hydraulic fluid to be pumped from the tank 31 to the wedge unit 30.

A coil spring 54 is circumposed on the rod 42 for normally urging the rod 42 and piston 43 into their raised positions.

The wedge unit 30 includes a housing 55, Figures 3 and 4, and formed integrally with the housing 55, or secured thereto is a rearwardly extending casing 56, the casing 56 being provided with a longitudinally extending bore 57, Figure 1. An opening 58 is arranged in the casing 56, the opening 58 serving as a pop-off valve, so that air in the bore 57 can properly bleed therethrough. Slidably or reciprocably arranged in the bore 57

is a plunger 59, and a stem or rod 60 has one end connected to the plunger 59. The rod 60 slidably projects through an aperture cap 64 which is arranged in threaded engagement with the end of the casing 56, and mounted on the outer end of the rod 60 is a U-shaped bracket 61 which serves to rotatably support a pulley 62. The pulley 62 is rotatably connected to the bracket 61 by means of a pin 65, and a cable or cord 63 is trained over the pulley 62 for a purpose to be later described.

The housing 55 is provided with a pair of opposed ports 68 and 67, and a bushing 68 is arranged in threaded engagement with the port 67, there being a similar bushing 69 arranged in threaded engagement with the other port 66. The conduit 34 is connected to the bushing 68, while the return conduit 35 is connected to the bushing 69. Rotatably supported in the housing 55 is a first valve 70, the valve 70 being provided with a pair of curved passageways 71 and 72. A second valve 73 is also rotatably mounted in the housing 55, and the valve 73 is provided with a curved passageway 74. A handle 75 is provided for manually rotating the valve 70, while a smaller handle 76 is provided for rotating the other valve 73. A passageway 77, Figure 3, extends through a portion of the housing 55 and serves to at times connect the bore 57 to the valve 70. A small passageway 78 also serves to selectively connect the valve 70 to an opening 79 which is arranged in a packing ring 80, so that hydraulic fluid can at times pass through the passageway 78 and opening 79 into the interior of a sleeve 81 for a purpose to be later described. A passageway 82 leads from the bushing 68 to the valve 70, and a similar passageway 83 leads from the other bushing 69 to the opposite side of the valve 70. A branch passageway 84 serves to connect the passageway 82 to the second valve 73, and the valve 73 is adapted to be connected to the passageway 83 by means of an L-shaped passageway 85. A spring 86 is provided for the valve 73, while a similar spring 87 is provided for the other valve 70, the springs 86 and 87 serving to prevent accidental rotation of these valves.

The sleeve 81 is provided with left-hand threads 88 and right-hand threads 89, Figures 3 and 4. A cap 90 is arranged in threaded engagement with the right-hand threads 89, and a packing ring 91 is interposed between the cap 90 and the end of the sleeve 81. Slidably or reciprocably arranged in the sleeve 81 is a piston 92, the front end of the piston 92 being shaped to define a wedge 93. A head 94 is secured to the rear end of the piston 92 by means of a screw 95, Figure 3. Thus, when hydraulic fluid is introduced into the sleeve 81, the piston 92 and wedge 93 will be forced forwardly. It will be seen that the front end of the housing 55 is shaped to provide a chamber into which is threaded the sleeve 81.

The wedge unit of the present invention further includes a plurality of body members 96, each of which has one end pivotally connected to the housing 55 by means of pins 97. Pins 98 also serve to pivotally connect the body members 96 to a pair of pivotally mounted jaws 99. Each of the jaws 99 has a curved or arcuate shape, and the jaws 99 are provided with a plurality of spaced teeth 100, so as to facilitate the gripping of the jaws into the tree being felled.

The cable 63 is trained over a pair of guide pulleys 101 which are rotatably connected to brackets 102 by means of a bolt-and-nut assembly or pin 103, Figure 1. The ends of the

cable 63 are connected to ears 104 which are secured to the wedge 93. Thus, when the piston 92 and wedge 93 move forwardly from the position shown in Figure 3 to the position shown in Figure 4, the plunger 59 will be moved forwardly in the bore 57. Likewise, when the valves are set so that the plunger 59 is moved rearwardly in the bore 57, the cable 63 will cause the piston 92 and wedge 93 to move rearwardly in the wedge unit.

The wedge 93 is provided with a plurality of spaced, parallel cutouts 105, Figures 7, 8 and 12, and arranged opposite to each of the cutouts 105 in the wedge 93 is a similar cutout 106 which is arranged on the inner face of the jaws 99. The cutouts 105 and 106 coact to provide bearing races, and a plurality of elliptical bearings 107 are arranged in the bearing races. These bearings 107 constantly rotate, and it will be seen from Figure 7, and from Figures 3 and 4, that there is sufficient space in these bearing races to enable the bearings 107 to constantly rotate, whereby the jaws and wedge will move smoothly relative to each other. If desired, ball bearings 108 can be used in lieu of the elliptical bearings 107, as shown in Figure 9, and the ball bearings 108 are, of course, arranged in suitably shaped bearing races.

A means is provided for guiding the wedge 93 during its sliding movement. This means comprises a plurality of guide ribs 109 which are secured to the inner surfaces of the jaws 99 by bolts 110. Each of the guide ribs 109 is provided with an inclined edge 111, Figure 10, and the inclined edge 111 slidably projects into a recess or groove 112 in the wedge 93. Thus, the wedge 93 can move back and forth, and the guide members 109 will insure that the wedge does not get out of alignment.

Spring means are provided for normally urging the pair of jaws 99 toward each other. This spring means includes coil springs 114 which have their ends secured to exteriorly threaded bushings 115, there being a nut 116 arranged on each of the bushings 115, Figures 7, 13 and 14. By adjusting the nuts 116, the tension on the coil springs 114 can be adjusted as desired.

In using the assembly of the present invention, a face cut is first made in the tree by means of a suitable saw or other tool. During the sawing of the trees, the upper and lower parts of the tree tend to bind on the saw, whereupon further movement of the saw is prevented. However, by means of the assembly of the present invention, the upper and lower parts of the tree can be maintained separated or spread apart sufficiently so that binding or pinching of the saw blade will be prevented. Thus, after the face cut in the tree has been made, the wedge unit 30 is positioned therein in the back cut behind the cutting bark, so that the pair of jaws 99 engage the upper and lower parts of the tree. In Figure 4 the jaws 99 are shown in their expanded position, so that the upper and lower parts of the tree will be maintained separated from each other. To have the parts move from the position shown in Figure 3 to the position shown in Figure 4, the valve 73 is rotated by means of the handle 76, so that no hydraulic fluid will flow through the passageway 74. Then, the valve 70 is rotated or set by means of the handle 75, so that hydraulic fluid will be pumped by the pump 32 from the tank 31, through the conduit 33, then through the conduit 34, then through the passageway 82, and finally through the passage-

way 72, and thence through the opening 79 into the interior of the sleeve 81, whereupon the piston 92 will be forced forwardly. As the piston 92 moves forwardly, the wedge 93 will cause the jaws 99 to move or pivot outwardly, as shown in Figure 4.

During this forward movement of the piston 92 and wedge 93, the cable 63 will cause the plunger 59 to move forwardly in the bore 57, since the cable 63 is connected to the wedge 93. Any air which is in the bore 57 will either pass out through the pop-off opening 58 or through the passageway 71, then through the passageway 83, and out through the conduit 35. To 10 retract the wedge 93, or cause the wedge 93 to move from the position shown in Figure 4 to the position shown in Figure 3, the valve 73 and valve 70 are adjusted as follows: The valve 73 is arranged so that no fluid flows therethrough, while the valve 70 is arranged so that the passageway 77 is connected to the short passageway 82 by means of the passageway 71 in the valve 70. Then it will be seen that the other passageway 72 will connect the opening 79 with the passageway 83. Thus, hydraulic fluid will pass through the 15 passageway 82, then through the passageway 71 in the valve 70, then through the passageway 77, to cause the piston 59 to move rearwardly in the bore 57, whereby the cable 63 will retract the piston 92 and wedge 93. The hydraulic fluid that is arranged in the sleeve 81 will be forced up through the opening 79 and then through the passageway 72, and then through the passageway 83, and be returned to the tank 31 through the conduit 35. To shut off the wedge unit, the 20 valve 73 and valve 70 are arranged as shown in Figure 3, so that no hydraulic fluid will flow therethrough.

The ball bearings of the wedge insure that there will be smooth movement between the various parts, and the springs 114 tend to normally urge the pair of jaws together. The tension on the springs 114 may be adjusted as desired. The wedge unit of the present invention is especially suitable for spreading a kerf crack in wood, and the wedge unit is constructed so that the wood will not be unduly smashed, cracked or otherwise harmed during the felling of the tree.

What is claimed is:

1. In combination, a tank adapted to hold hydraulic fluid, a wedge unit, a first conduit connecting said tank to said wedge unit, a pump for pumping hydraulic fluid from said tank through said conduit to said wedge unit, and a chain-operated cam for actuating said pump, said wedge unit comprising a housing provided with a pair of opposed ports, said first conduit communicating with one of said ports and a second conduit connecting the other port to said tank, a casing projecting rearwardly from said housing and provided with a longitudinally extending bore, a plunger slidably arranged in said bore, a stem connected to said plunger, there being a chamber arranged in said housing, a hollow sleeve arranged in threaded engagement with said chamber, a first manually operable valve rotatably arranged in said housing and provided with a pair of passageways for connecting said ports to said bore and to said sleeve, a second valve 10 rotatably positioned in said housing for permitting the hydraulic fluid to by-pass the first valve, a plurality of body members pivotally connected to said housing, a pair of arcuate jaws pivotally connected to said body members and provided with a plurality of exterior teeth, a piston slidably arranged in said sleeve, and a wedge formed integrally with said piston for causing pivotal movement of said jaws, a pulley mounted on the free end of said stem, ears secured to said wedge, guide pulleys positioned exteriorly of said housing, and a cable trained over all of said pulleys and having its ends attached to said ears.

2. In a wedge unit, a housing provided with a pair of opposed ports, a casing projecting rearwardly from said housing and provided with a longitudinally extending bore, a plunger slidably arranged in said bore, a stem connected to said plunger, there being a chamber arranged in said housing, a hollow sleeve arranged in threaded engagement with said chamber, a first manually operable valve rotatably arranged in said housing and provided with a pair of passageways for connecting said ports to said bore and to said sleeve, a second valve rotatably positioned in said housing for permitting the hydraulic fluid to by-pass the first valve, a plurality of body members pivotally connected to said housing, a pair of arcuate jaws pivotally connected to said body members and provided with a plurality of exterior teeth, a piston slidably arranged in said sleeve, and a wedge formed integrally with said piston for causing pivotal movement of said jaws, bearing races arranged between said jaws and wedge, and spring members for normally urging said jaws toward each other, a pulley mounted on the free end of said stem, ears secured to said wedge, guide pulleys positioned exteriorly of said housing, and a cable trained over all of said pulleys and having its ends attached to said ears.

3. In a wedge unit, a housing provided with a pair of opposed ports, a casing projecting rearwardly from said housing and provided with a longitudinally extending bore, there being an opening in said casing defining a pop off valve, a plunger slidably arranged in said bore, a stem connected to said plunger, an apertured cap mounted on the rear end of said casing and slidably receiving said stem, there being a chamber 25 arranged in said housing, a hollow sleeve arranged in threaded engagement with said chamber, a first manually operable valve rotatably arranged in said housing and provided with a pair of curved passageways for connecting said ports to said bore and to said sleeve, a second valve 30 rotatably positioned in said housing and provided with a curved passageway for permitting hydraulic fluid to by-pass the first valve, there being a passageway extending through a portion of said housing and connecting said first valve to said bore, there being a passageway connecting said first valve to said sleeve, a plurality of body members pivotally connected to said housing, a pair of arcuate jaws pivotally connected to said body members and provided with a plurality of exterior teeth, a piston slidably arranged in said sleeve, a head secured to the rear end of said piston, and a wedge formed integrally with said piston for causing pivotal movement of said jaws, ears secured to said wedge, guide pulleys positioned exteriorly of said housing, and a cable trained over all of said pulleys and having its ends attached to said ears.

4. In a wedge unit, a housing provided with a pair of opposed ports, a casing projecting rearwardly from said housing and provided with a longitudinally extending bore, there being an opening in said casing defining a pop off valve, a plunger slidably arranged in said bore, a stem connected to said plunger, an apertured cap mounted on the rear end of said casing and slidably receiving said stem, there being a chamber 40 arranged in said housing, a hollow sleeve arranged in threaded engagement with said chamber, a first manually operable valve rotatably arranged in said housing and provided with a pair of curved passageways for connecting said ports to said bore and to said sleeve, a second valve 45 rotatably positioned in said housing and provided with a curved passageway for permitting hydraulic fluid to by-pass the first valve, there being a passageway extending through a portion of said housing and connecting said first valve to said bore, there being a passageway connecting said first valve to said sleeve, a plurality of body members pivotally connected to said housing, a pair of arcuate jaws pivotally connected to said body members and provided with a plurality of exterior teeth, a piston slidably arranged in said sleeve, a head secured to the rear end of said piston, and a wedge formed integrally with said piston for causing pivotal movement of said jaws, ears secured to said wedge, guide pulleys positioned exteriorly of said housing, and a cable trained over all of said pulleys and having its ends attached to said ears said wedge being provided with a plurality of spaced parallel cutouts, there being a plurality of cutouts in the inner faces of said jaws arranged opposite to the cutouts in said wedge providing bearing races, a plurality of elliptical bearings rotatably arranged in said races, guide means for maintaining said wedge in alignment during

its sliding movement, said guide means comprising a plurality of guide ribs secured to the inner surfaces of said jaws, each of said guide ribs being provided with an inclined edge, there being recesses in said wedge for receiving said inclined edges, and spring means for normally urging said pair of jaws towards each other, said spring means including bushings adjustably connected to said jaws, and coil springs having their ends secured to said bushings.

4. In a wedge unit, a housing provided with a pair of ports, a casing projecting rearwardly from said housing and provided with a bore, there being an opening in said casing defining a pop off valve, a plunger slidably arranged in said bore, a stem connected to said plunger, an apertured cap mounted on said casing and slidably receiving said stem, a pulley mounted on said stem, there being a chamber arranged in said housing, a sleeve arranged in engagement with said chamber, a first manually operable valve rotatably arranged in said housing and provided with a pair of passageways for connecting said ports to said bore and to said sleeve, a second valve rotatably positioned in said housing and provided with a passageway for permitting hydraulic fluid to by-pass the first valve, there being a passageway extending through a portion of said housing and connecting said first valve to said bore, there being a passageway connecting said first valve to said sleeve, a plurality of body members pivotally connected to said housing, a pair of jaws pivotally connected to said body members and provided with a plurality of teeth, a piston slidably arranged in said sleeve, 35

a head secured to the rear end of said piston, a wedge formed integrally with said piston for causing pivotal movement of said jaws, ears secured to said wedge, guide pulleys positioned exteriorly of said housing, a cable trained over all of said pulleys and having its ends attached to said ears, said wedge being provided with a plurality of cutouts, there being a plurality of cutouts in said jaws providing bearing races, a plurality of bearings rotatably arranged in said races, guide means for maintaining said wedge in alignment during its sliding movement, said guide means comprising a plurality of guide ribs secured to said jaws, each of said guide ribs being provided with an inclined edge, there being recesses in said wedge for receiving said inclined edges, and spring means for normally urging said pair of jaws towards each other, said spring means including bushings adjustably connected to said jaws, and coil springs having their ends secured to said bushings.
